CLOTH MEASURING INSTRUMENT

John W. Holman, Wellington, Kans.

Application March 11, 1955, Serial No. 35,003

Term of patent 14 years

(Cl. D52—1)

Fig. 1.

Fig. 3.

Fig. 2.

Fig. 1 is a perspective view of a cloth measuring instrument showing my new design;

Fig. 2 is a bottom plan view thereof; and

Fig. 3 is an end elevational view thereof.

I claim:

The ornamental design for a cloth measuring instrument, as shown.
